UNITED STATES PATENT OFFICE.

MAURICE O'CONNELL, OF WILKES-BARRE, PENNSYLVANIA.

DESIGN FOR A FLAG.

56,376.

Specification for Design.

Patented Oct. 5, 1920.

Application filed December 2, 1919. Serial No. 342,033. Term of patent 3½ years.

To all whom it may concern:

Be it known that I, MAURICE O'CONNELL, a citizen of the United States, residing at Wilkes-Barre, in the county of Luzerne and State of Pennsylvania, have invented a new, original, and ornamental Design for Flags, of which the following is a specification, reference being had to the accompanying drawing, forming a part thereof.

The figure is a plan view of a flag, showing my new design.

The flag consists of three longitudinal stripes or bars of equal width, the central

one being white. Extending transversely through the center of the flag and separating the central white stripe into two sections, and separating the sections of the side bars or stripes, is a narrow red stripe or bar. The bars or stripes adjacent the staff end of the flag are red, white and blue, while the remote ones are green, white and orange.

I claim:

The ornamental design for a flag, as shown and described.

MAURICE O'CONNELL.
